UNITED STATES PATENT OFFICE.

JOHN EDWARD OGDEN, OF BROOKLYN, NEW YORK.

WALL-SOCKET.

1,107,544.

Specification of Letters Patent. Patented Aug. 18, 1914.

Application filed August 14, 1913. Serial No. 784,868.

To all whom it may concern:

Be it known that I, JOHN EDWARD OGDEN, a citizen of the United States of America, and a resident of Brooklyn, county of Kings, 5 and State of New York, have invented certain new and useful Improvements in Wall-Sockets, of which the following is a specification, reference being had to the accompanying drawings, forming a part thereof.

10 My invention relates to wall plugs or sockets such as are driven into holes in walls, floors or other structures to provide anchorages for threaded bolts.

15 The object of this invention is to provide a simple and inexpensive device which has advantages over those which hitherto have been known.

20 Referring to the drawings, Figure 1 is a sectional elevation of a wall with a wall socket which embodies my invention embedded in a hole therein and this figure also shows an object secured to the wall by means of a bolt screwed into the socket. Fig. 2 is a sectional longitudinal elevation, and Fig. 3 25 an end view of a wall socket made according to my invention but of slightly different form from that shown in Fig. 1. Fig. 4 is an end elevation of a socket which is elliptical in cross section. Another form of my invention is shown in sectional longitudinal elevation and end view respectively in Figs. 30 5 and 6. In Figs. 7 and 8 another modification, with the outer fins or ribs placed only at the ends of the device, is shown in longitudinal section and in transverse section respectively, the section in Fig. 8 being taken 35 on the line 8—8 of Fig. 7. Another modified construction is shown in longitudinal elevation partly in section in Fig. 9, and in end view in Fig. 10. These two figures show the 40 fins or holding ribs normal to the axis of the device. These ribs are shown in helices in Figs. 11 and 12 of which Fig. 11 is a longitudinal elevation partly in section and Fig. 12 is an end elevation.

45 Like characters of reference designate corresponding parts in all the figures.

In all of the modifications shown, the plug or socket comprises a circumferentially continuous hollow shell 10, the inside of which is provided with means for receiving the threads of a bolt, and from the outside of which project a plurality of parallel overlapping holding fins or ribs which are more 50 or less flexible. These fins are designated by the reference numeral 11.

In Fig. 2 the fins are tapered so that the portions of them at the outer end of the shell stand out from the shell a greater distance than do those portions which are at the 60 inner end of the shell. In this and some of the other figures of the drawings the shell is internally threaded as at 12 to receive the threaded shank of a bolt 13, or other desired device. It is sometimes desirable to counter-sink the outer end of the shell as at 14 so 65 that if the plug or socket is driven into a hole with a hammer, the threads 12 will not be injured thereby.

70 Before describing the modifications illustrated in the other figures of the drawings, I will describe the manner in which this device is used, referring particularly to Figs. 1, 2 and 3. In Fig. 1, 20 designates a wall of concrete or other material into which a 75 bolt cannot be conveniently screwed, and 21 is a hole drilled therein to a depth somewhat in excess of the length of the socket. The diameter of this hole is slightly less than the external diameter of the socket. The socket 80 is then driven into the hole which causes the fins to be pressed inward a sufficient amount to allow the socket to enter. If the fins are tapered longitudinally as they are shown in Fig. 2, the plug will enter the hole with but 85 little resistance, which resistance will increase as the plug goes farther into the hole.

90 The compressed overlapping fins form an effective means for holding the device in the wall or other structure so that it will remain 95 in the wall. It is to be noted that the fins are inclined from the periphery of the shell in a common direction corresponding with the direction given a right-handed screw when turned into place. This causes the edges of the fins to oppose any tendency of the shell to turn with the bolt.

99 The device may be made of either hard or soft metal. If of soft metal it may be either internally threaded as shown at 12 in some 100 of the figures, or it may be so arranged that the bolt will cut the threads when it is inserted. For example, the bore of the shell may be elliptical or of a form the cross-section of which is a curved plane of non-uniform diameter, as is shown at 15 in Fig. 4. The external cross-section of the shell is shown in Fig. 4 and designated by 10^a, is also a curved plane of non-uniform diameter. It is obvious also that the shell itself 105 may be cylindrical with the line drawn through the outer edges of the fins of the

form shown in this figure. Another convenient construction in which the bolt may cut threads is illustrated in Figs. 5 and 6, in which are internal longitudinally disposed projections or ribs 16. In Fig. 5 the shell 10^B is externally tapered and the parts 11^A of the fins parallel with the outer surface thereof. The parts 11^B of the fins flare outwardly as shown. This is a distinct advantage, for in drilling holes such as that shown at 21 in Fig. 1 by hand, the outer part thereof is apt to be of larger diameter than the rest of the hole and the flare on the ribs not only centers the socket but more closely 15 fills up the outer end of the hole. Similarly flared fins are shown at 11^C near the outer end of the shell in Fig. 7, but these are not continuous. Near the inner end of the shell are other fins 11^D while the intermediate 20 part of the shell is in this case without fins.

This invention is not limited to longitudinally disposed holding fins. In Figs. 9 and 10 for example, I have shown similar overlapping holding fins or ribs 17 which are at 25 right angles to the axis of the shell. And in Figs. 11 and 12 the fins, designated by 18 are helically disposed.

I have illustrated several modifications of the invention to show that it is not limited 30 to any specific form or construction, but that many designs and devices may be made within the scope of the claims.

What I claim is:

1. A wall socket comprising a hollow 35 shell having overlapping compressible holding fins projecting from its outer surface whereby when the socket is introduced into a recess having hard walls compression of the fins serves to anchor the socket.

40 2. A wall socket comprising a hollow shell having parallel overlapping compressible holding fins projecting from its outer surface whereby when the socket is introduced into a recess having hard walls compression of the fins serves to anchor the socket.

45 3. A wall socket comprising a hollow shell having parallel overlapping transversely tapered compressible holding fins projecting from its outer surface, and means within said shell for receiving the threads of a bolt whereby when the socket is introduced into a recess having hard walls compression of the fins serves to anchor the socket.

4. A wall socket comprising a hollow 55 shell having longitudinally extending compressible holding fins projecting at an angle to its radii from its outer surface whereby when the socket is introduced into a recess having hard walls compression of the fins 60 serves to anchor the socket.

5. A wall socket comprising a hollow internally threaded shell having longitudinally extending overlapping compressible holding fins projecting from its outer surface whereby when the socket is introduced into a recess having hard walls compression of the fins 65 serves to anchor the socket.

6. A wall socket comprising a hollow internally threaded cylindrical shell having 70 longitudinally extending overlapping tapered compressible holding fins projecting from its outer surface whereby when the socket is introduced into a recess having hard walls compression of the fins 75 serves to anchor the socket.

7. A wall socket comprising a circumferentially continuous hollow cylindrical shell having longitudinally extending overlapping compressible holding fins projecting 80 from its outer surface and extending over the length of the shell, said fins being tapered longitudinally and transversely, and means within said shell for receiving the threads of a bolt whereby when the socket 85 is introduced into a recess having hard walls compression of the fins serves to anchor the socket.

8. A wall socket comprising a circumferentially continuous hollow internally threaded cylindrical shell having longitudinally extending overlapping compressible holding fins projecting from its outer surface and extending over the length of the shell, said fins being tapered longitudinally and transversely, the outer end of said shell being 95 provided with an internal recess whereby when the socket is introduced into a recess having hard walls compression of the fins serves to anchor the socket.

In testimony whereof, I have hereunto set my hand in the presence of two subscribing witnesses, this 29th day of July, 1913.

JOHN EDWARD OGDEN.
